CLAIM

The ornamental design for an electronic vaping system, as shown and described.

DESCRIPTION

FIG. 1 is a perspective view of a new design for an electronic vaping system.

FIG. 2 is a top view of the system of FIG. 1.

FIG. 3 is a bottom view of the system of FIG. 1.

FIG. 4 is a left side view of the system of FIG. 1.

FIG. 5 is a right side view of the system of FIG. 1.

FIG. 6 is a front view of the system of FIG. 1.

FIG. 7 is a back view of the system of FIG. 1.

FIG. 8 is a perspective view of another embodiment of the new design for an electronic vaping system.

FIG. 9 is a top view of the system of FIG. 8.

FIG. 10 is a bottom view of the system of FIG. 8.

FIG. 11 is a left side view of the system of FIG. 8.

FIG. 12 is a right side view of the system of FIG. 8.

FIG. 13 is a front view of the system of FIG. 8.

FIG. 14 is a back view of the system of FIG. 8.

FIG. 15 is a perspective view of another embodiment of the new design for an electronic vaping system.

FIG. 16 is a top view of the system of FIG. 15.

FIG. 17 is a bottom view of the system of FIG. 15.

FIG. 18 is a left side view of the system of FIG. 15.

FIG. 19 is a right side view of the system of FIG. 15.

FIG. 20 is a front view of the system of FIG. 15; and,

FIG. 21 is a back view of the system of FIG. 15.

Broken lines in the drawings depict portions of the electronic vaping system that form no part of the claimed design.
